UNITED STATES PATENT OFFICE

158,401

DESK STAPLER

Curt E. Nyberg, Chicago, Ill., assignor to Vail
Manufacturing Company, Chicago, Ill., a corporation of Illinois

Application October 8, 1949, Serial No. 5,389

Term of patent 14 years

(Cl. D74—1)

To all whom it may concern:

Be it known that I, Curt E. Nyberg, a citizen of the United States, residing at Chicago, Cook County, Illinois, have invented a new, original, and ornamental Design for a Desk Stapler, of which the following is a specification, reference being had to the accompanying drawing, forming part thereof, wherein:

Figure 1 is a perspective view of a desk stapler showing my new design;

Fig. 2 is a side elevation thereof;

Fig. 3 is a top plan view thereof; and

Fig. 4 is an elevational view of the stapler end from which the staples are discharged.

I claim:

The ornamental design for a desk stapler, as shown.

CURT E. NYBERG.
